UNITED STATES PATENT OFFICE.

HERBERT E. VAN DORN, OF CHICAGO, ILLINOIS.

UNIVERSAL-JOINT ANCHOR FOR DRAWBARS.

Application filed September 14, 1921, Serial No. 500,531. Renewed March 8, 1923.

My invention has for its object to produce a simple and novel means for anchoring the inner end of a drawbar which must be capable of swinging in a vertical plane 5 and also in a horizontal plane.

The various features of novelty whereby my invention is characterized will herein-after be pointed out with particularity in the claims; but, for a full understanding of 10 my invention and of its object and advantages, reference may be had to the following detailed description taken in connection with the accompanying drawings, wherein:

Figure 1 is a top plan view of an anchoring device arranged in accordance with the preferred form of my invention;

Fig. 2 is a side elevation;

Fig. 3 is a section taken approximately on line 3—3 of Fig. 1;

20 Fig. 4 is a perspective view of the anchoring pin used in the construction shown in Figs. 1, 2 and 3;

Fig. 5 is a top plan view of a modified form of anchoring device;

25 Fig. 6 is a section taken approximately on line 6—6 of Fig. 5;

Fig. 7 is a perspective view of the anchoring pin employed in the construction shown in Figs. 5 and 6;

30 Fig. 8 is a section taken approximately on line 8—8 of Fig. 5;

Fig. 9 is a top plan view of a still further modified form of anchoring device;

Fig. 10 is a side elevation of the device 35 shown in Fig. 9;

Fig. 11 is a section taken approximately on line 11—11 of Fig. 9;

Fig. 12 is a section taken approximately on line 12—12 of Fig. 9; and

40 Fig. 13 is a perspective view of the anchoring pin forming part of the construction shown in Figs. 9 to 12.

Referring to Figs. 1 to 4 of the drawings, 1 represents a plate adapted to be fastened 45 to the underframe of a railway car. The forward portion of the plate has a depressed portion 2 provided with a flattened bottom 3. The rear wall of the depressed portion is continued downwardly as indicated at 4, 50 and is then carried forwardly in the form of a part 5 lying at some distance below and parallel with the flattened part 3. The jaw thus formed is stiffened and braced by means of two parallel webs 7 extending 55 downwardly from the rear edge of the plate 1 and underneath the forwardly-projecting

part 5; the webs being integrally connected with the members 4 and 5. In the parts 3 and 5 are placed axially aligned round holes 8 and 9 respectively, the hole 8 being larger 60 in diameter than the hole 9. The members 3 and 5 are stiffened in the vicinity of the holes by means of annular flanges 10 and 11 surrounding these respective holes. 12 is an anchoring pin whose largest diameter 65 is no greater than the diameter of the upper hole 8 and which has at the lower end a reduced cylindrical part 13 which fits rotatably in the hole 9; the upper end of the pin fitting rotatably in the hole 8. Therefore 70 the pin may be placed in position or removed by simply lowering it or raising it through the top of the plate.

The drawbar 14 which is to be anchored to the plate has at its rear end a jaw 15 75 adapted to enter the space between the parts 3 and 5 of the fixed anchoring member or casting and embrace the anchoring pin. The anchoring pin and the jaw are pivotally connected together by means of a transverse pin or pintle 16 passing through the same; the pin or pintle 16 being fastened in any suitable way as, for example, by providing it at one end with a head and placing a cotter pin 17 through the other end. 80 The anchoring pin is preferably flattened on opposite sides as indicated at 18 so as to afford comparatively wide bearing surfaces between the same and the side to the jaw. 85

It will be seen that the drawbar may be 90 swung in a horizontal plane through a large angle by causing the anchoring pin to turn with it. The drawbar may also be swung up and down in a vertical plane about the hinge pin 16. Before the anchoring pin is 95 pinned to the inner end of the drawbar it may be moved into and out of position, but, after the connection between the anchoring pin and the drawbar has been made, the drawbar prevents the anchoring pin from 100 being lifted out of its bearings. Therefore the attachment between the anchoring pin and the drawbar may be said to serve also as a locking means to prevent accidental displacement of the anchoring pin. I have 105 therefore produced an anchoring attachment for the inner end of the drawbar which consists of a few simple elements which may readily be assembled and disconnected from each other, and which are strong and durable 110 so as to insure long life.

In Figs. 5 to 8 inclusive I have shown a

somewhat different form of my invention. The anchoring casting is the same as that heretofore described, but the anchoring pin 20 has a somewhat different form than the pin 12. The upper end of the pin 20 has a portion 21 of reduced diameter and this, instead of fitting into the hole or bearing 8, fits rotatably in a sleeve 22 arranged within the hole or bearing 8. The pin and the sleeve are held against displacement by means of a cover plate 23 lying above the same, preferably upon and making a tight fit with the annular flange 10; the cover plate being fastened in position by means of suitable bolts or studs 24. It will be seen that the cover plate not only holds the anchoring pin against displacement, both when the drawbar is attached to the anchoring pin and when the drawbar is disconnected, but also acts as a cover or shield to prevent the entrance of water and dirt into the bearing for the upper end of the pin.

In Figs. 9 to 13 inclusive I have shown a still further modification in which the anchoring casting is made in two parts which must be separated from each other in order to place the anchoring pin in position or remove it. The plate 25, corresponding to the plate 1, has the depressed portion 2 provided with a flat bottom 3. Instead of the integral underlying member 5, I have provided an auxiliary plate 26 which is attached to a downward bracket-like extension 27 extending downwardly from the plate 25 in rear of and partly surrounding the depressed portion 2; the plate 26 being fastened to the bracket-like part by means of a number of bolts 28. The anchoring pin 29, in this instance, has reduced upper and lower ends as indicated at 30 and 31. If desired, the body or intermediate portion of the anchoring pin may be made square or rectangular. The holes 32 and 33 in the parts 3 and 26 respectively are made just large enough to receive the reduced ends 30 and 33 of the anchoring pin. In order to place the anchoring pin in position, the plate 26 must be detached, and this plate must also be detached before the anchoring pin can again be removed. However, the drawbar may be fastened to the anchoring pin or disconnected therefrom without disturbing the anchoring pin. While the device just described may not be quite as simple as that disclosed in Figs. 1 to 4, it is just as rugged and possesses what may sometimes be considered an advantage, namely the capacity of locking the anchoring pin

against accidental displacement even after the drawbar has been disconnected.

While I have illustrated and described with particularity only a few preferred forms of my invention I do not desire to be limited to the exact details thus illustrated and described; but intend to cover all forms and arrangements which come within the terms employed in the definitions of my invention constituting the appended claims.

I claim:

1. In combination, a flat plate having at the front a flat-bottomed depressed portion, a bracket-like part projecting downwardly from the rear portion of the plate behind said depressed portion, and a forwardly-extending cantilever member at the lower end of said bracket-like part lying parallel with and below the bottom of said depressed portion; a vertical anchor pin extending between and revolvably supported at its ends by the flat bottom of said depressed portion and said cantilever; and a drawbar hinged to said pin so as to be capable of swinging vertically thereon.

2. In combination, an anchor member having upper and lower elements spaced apart from each other, a vertical pin extending between said elements and journaled at its upper end in said upper element, the lower end of the pin being reduced in diameter and being fitted to rotate in a bearing in the lower element, the journal opening in the upper element being large enough to permit the removal of said pin through the same, a drawbar having a jaw embracing said vertical pin, and a transverse pivot pin passing through the members of said jaw and said vertical pin, said jaw being of such a depth that it approximately fills the space between the upper and lower elements of said anchor member.

3. In combination, a flat plate having at the front a flat-bottomed depressed portion, a downwardly-extending part in rear of said portion, a forwardly-extending member connected to the lower end of the downwardly-extending part and lying below and parallel with the flat bottom of said depressed portion, a vertical anchor pin extending between and rotatably supported by the aforesaid member and said depressed portion, a drawbar having a jaw embracing said vertical pin, and a transverse pivot pin passing through said jaw and said vertical pin.

In testimony whereof, I sign this specification.

HERBERT E. VAN DORN.
